POINTER FOR PHOTO RETOUCHING
PENCILS

Harry Le Roy Adams, Denver, Colo.

Application July 17, 1948, Serial No. 39,298

2 Claims. (Cl. 120—95)

1

This invention relates to a pencil sharpener and more particularly to a pencil sharpener for sharpening the long pencil leads employed in photographic retouching pencils. Retouching pencils are sharpened with an exceedingly long pointed lead from 1" to 3" in length. These long leads must be accurately tapered to very fine points. It is an exceedingly difficult and time consuming operation to taper these leads to the desired taper and the operation must be constantly repeated during the retouching operation.

The principal object of this invention is to provide a sharpener for quickly, easily and accurately forming a long pointed taper on the lead of the retouching pencil.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved retouching pencil lead sharpener;

Fig. 2 is a vertical cross section therethrough taken on the line 2—2, Fig. 1;

Fig. 3 is a longitudinal section taken on the line 3—3, Fig. 2;

Fig. 4 is a vertical section taken on the line 4—4, Fig. 3; and

Fig. 5 is a detail sectional view illustrating an abrasive disc mounting employed in the improved sharpener.

The improved retouching pencil lead sharpener is supported from a base 10, which may be attached to any suitable supporting surface in any desired manner.

A bifurcated bracket 11 extends from the base 10 to support the sharpener mechanism. A circular end plate 12 is secured to and clamped against the bracket leg 11 by means of a clamp screw 13 which slides into the furcation in the bracket 11. A cup-shaped housing 14 is permanently attached around its open end to the periphery of the plate 12 so as to be supported by the latter. The housing 14 is provided with an open window 15 in its side.

An operating shaft 16 extends throughout the length of the housing 14 to one side of the axis thereof. The shaft 16 is rotatably mounted in the plate 12 and at its one extremity is threaded

into a rotatable shaft nut 17 which is mounted in the head of the housing 14. The shaft 16 terminates at its other extremity in a suitable manual crank 18.

5 A shaft block 19 is rotatably mounted about the shaft 16 adjacent the plate 12. The shaft block 19 supports a stub shaft 20 which is threaded into a tapped hole in the side of the block 19. The outer extremity of the stub shaft 20 projects

10 through the window 15. A toothed bevel pinion 25 is rotatably mounted on the stub shaft 20 against the block 19. The pinion 25 has an elongated hub over which a threaded sleeve 21 is forced. The sleeve 21 carries a flange 22 against which a circular abrasive disc 23, of sand paper, emery cloth or the like, is clamped by means of a clamp nut 24 which is threaded on sleeve 21. The entire assembly is prevented from moving outward by means of a 15 shoulder flange 33 formed on the shaft 20. The outer extremity of the shaft 20 is preferably flattened to form a finger grip 35.

The pinion 25 is in constant mesh with a bevel gear 26 which is locked on the shaft 16, against 20 the end of the block 19, by means of a suitable set screw 34. The gear 26 is relatively longer than the pinion 25 so that rotation of the crank 18 results in rapidly whirling the abrasive disc 23.

The pencil to be sharpened, indicated in 25 broken line at C, is passed through a rubber sleeve 27 contained within a rotary collet tube 28 which rotates within a tubular bearing 29 fixedly mounted in the head of the housing 14. A wedge bushing 30 is threaded into the outer 30 end of the collet tube 28. The extremities of the rubber sleeve 27 are tapered and the inner diameters of the collet tube 28 and the bushing 30 are also tapered so that when the bushing 30 is threaded into collet tube 28, the rubber sleeve 27 will be radially expanded to grip the pencil.

A driven gear 32 is mounted on the collet tube 28 within the housing 14 and is in constant mesh with a drive gear 31 which is threaded on the extremity of the shaft 16, so that, as the crank 18 is rotated the collet tube 28 and the pencil therein will be similarly rotated in an opposite direction and at substantially the same speed.

In use, the pencil is passed through the rubber sleeve 27 until its elongated lead overlies the abrasive disc 23, as indicated at the broken line at A in Fig. 1.

The bushing 30 is then tightened to cause the rubber sleeve to grip the pencil. The stub shaft 20 is supported by the fingers of the operator and the crank 18 is rotated. The extremity of the

stub shaft is lowered bringing the upper surface of the abrasive disc 23 in contact with the lead A. By controlling the amount of rotation of the crank 18 and the amount of pressure on the stub shaft 20 the degree of grinding can be accurately controlled and bring the lead A to a sharp accurate point.

It is desired to call attention to the fact that the stub shaft 20 does not extend at an exact right angle to the axis of the shaft 16. The axis of the former is inclined toward the pencil extremity of the sharpener at approximately 3°, as indicated by the broken lines B in Fig. 3. This inclines the abrasive disc 23 from the axis of the pencil to produce an accurate six degree point on the pencil lead.

It is also desired to call attention to the fact that the amount of grinding can be accurately controlled by raising or lowering the protruding extremity of the stub shaft 20. This shaft must be lifted as the pencil is inserted so that the weight thereof will cause the disc to bear against the pencil lead A.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A sharpening device for pencil leads comprising: a support housing; an operating shaft rotatably mounted in said housing; means for rotating said shaft; a drive gear carried by said shaft; a driven gear in mesh with said drive gear; a tubular pencil gripping member carrying said driven gear and being rotatable therewith, said gripping member being rotatably mounted in said housing with its axis parallel to and to one side of said operating shaft; a block member mounted on said operating shaft, the latter be-

ing rotatable in the former; a stub shaft extending outwardly from said block; an abrasive disc rotatably mounted on said stub shaft; and means for transmitting rotation from said operating shaft to said abrasive disc.

2. A sharpening device for pencil leads comprising: a supporting housing; an operating shaft rotatably mounted in said housing; means for rotating said shaft; a drive gear carried by said shaft; a driven gear in mesh with said drive gear; a tubular pencil gripping member carrying said driven gear and being rotatable therewith, said gripping member being rotatably mounted in said housing with its axis parallel to and to one side of said operating shaft; a block member mounted on said operating shaft, the latter being rotatable in the former; a stub shaft extending outwardly from said block; an abrasive disc rotatably mounted on said stub shaft; a toothed bevel pinion fixed to said disc and mounted on said stub shaft; a bevel gear fixed on said operating shaft in mesh with said pinion to rotate said abrasive disc in consequence of the rotation of said operating shaft; and means for rotating said block member about the axis of said operating shaft to cause said disc to swing toward and away from the axis of said pencil gripping member.
